ERECTING PARTITION WALLS

Roger G. Jennings, Kensington, Calif., assignor to Pacific Vegetable Oil Corporation, San Francisco, Calif., a corporation of California

Filed Feb. 13, 1963, Ser. No. 258,261

4 Claims. (Cl. 50—70)

This invention relates to a method of constructing buildings, and more particularly to a simplified, quick procedure of manufacturing walls and ceilings with modular pre-fabricated panels in such a way that dismantling the building for subsequent reconstruction can be done with a minimum of time and labor.

A "curtain wall" building, well-known to the architectural profession, is a structure constructed with vertical columns and horizontal beams linked together into a rigid frame that maintains the building's primary structural integrity. This frame is enclosed by fastening sectional wall and ceiling panels, such as modulator "sandwich" panels, to it. A sandwich panel in general comprises a pair of substantially parallel "skins" made from plywood, sheet rock, paper or other similar wall surfacing, separated by a low density core material such as rigid plastic foam or a wooden frame.

The various methods heretofore used to attach the sandwich panels to the building frame and to each other, so as to provide a rigid water-tight structure, have not been fully satisfactory. One such method is to bolt the panels, but bolting is quite time consuming, is expensive, and alignment of the bolt holes is difficult, especially in reassembling the building, as at a new site. Riveting is another such method, but riveting is also very time consuming and expensive. Furthermore, when rivets are used, it becomes difficult and time consuming to dismantle the structure and often damages the areas around where the rivets were. All these mentioned methods also suffer from another disadvantage—they are not always completely water-tight.

An important object of my invention is to provide an improved method of quickly and securely fastening wall and ceiling panels to supporting columns and beams of a curtain wall building, and also to each other.

Another object of my invention is to provide an improved method of removably fastening wall and ceiling panels to supporting frames and to each other.

Another object of my invention is to provide an improved method for disconnecting wall panels from each other and from supporting columns and beams without damage to any of the structures involved.

Still another object of my invention is to provide a new method of establishing a rigid water-tight seal at the junctures of building panels and the supporting framework to which they are fastened.

Yet another object of my invention is to provide a sturdy, permanent-type building structure which can be quickly and easily assembled, disassembled, transported, and otherwise handled like a temporary, portable building.

In accordance with my invention, the rigid frames of curtain-wall buildings are constructed of columns and beams having an I-shaped cross section, such as conventional steel I-beams, positioned such that their webs are transverse to the plane of the wall or ceiling. Prefabricated sandwich panels or other suitable wall or ceiling enclosing structures are inserted between the flanges of adjacent columns and beams and securely but removably fastened to them by filling the joints with a pre-expanded plastic foam in such a way that the plastic foam holds the panels, the columns, and the beams together, filling in the openings between these elements tightly and rigidly

2

and bonding to the elements, to unite them into a strong, weather-tight structure.

No bolts, rivets or other types of fastening devices are required or used to connect the panels to their supporting members, yet the plastic bond is generally more sturdy and lasting than one made with bolts or rivets. In striking contrast to a bolted or riveted bond, in accordance with my invention this plastic bond can be broken and reestablished quickly, easily, and as often as desired with substantially no wear and tear on the panels or their supports. This means that a building constructed according to my invention can be dismantled, removed to another site, and reerected as other portable buildings, and yet provide the tightness, strength, and overall integrity heretofore provided only by non-portable so-called "permanent" structures.

Other objects and advantages of my invention will become apparent from the following description and the accompanying drawings in which:

20 FIG. 1 is a fragmentary view in side elevation of a portion of a curtain wall constructed according to my invention, showing two adjacent pre-fabricated wall panels joined to an I-beam supporting column, with a portion broken away to show the enclosed parts in section;

25 FIG. 2 is an enlarged view in section taken along the line 2—2 of FIG. 1, showing the device and arrangement for breaking the plastic foam seal between the panels and the beam; and

30 FIG. 3 is a view in section taken along the line 3—3 of FIG. 2, on a reduced scale, showing in solid lines the seal-breaking device in rest position and, in broken lines, the same device partially withdrawn.

Walls

35 As the drawings illustrate, in the preferred form of my invention, the wall 10 of a curtain-wall, rigid frame building comprises a series of spaced, vertical I-beam columns 11 supporting sandwich panels 12 which fit in between the flanges 13 and 14 of the columns 11 with one skin or surface 15 resting against one flange 13. The dimensions of the panels 12 or such that when they are in position between the columns 11, the other skin 16 is spaced from the other flange 14 and their end edges 17 are close to, but not abutting, the column's web 18. A rigid metal cap member 19 with a main body portion 20 and lateral flanges 21 and 22 rests against the skin 16 and forms an enclosed space at the joint with the skins 16, the panel end edges 17, and the column 11. A pre-expanded plastic foam 23 completely fills this enclosed space, serving both as a bonding agent to hold the panels 12, the column 11, and the end cap 19 together, and as a weather-tight seal for the joint. This plastic foam 23 so securely bonds the enclosing elements together that the joint is generally stronger and more permanent than one that is riveted or bolted.

40 Erecting this wall 10 is a relatively rapid procedure as compared with the prior-art procedures employing joints that are fastened by rivets, bolts or the like. After the columns 11 are in place, the wall panels 12 are installed by elevating them and then slipping them down between the flanges 13 and 14 of their supporting columns 11. Each panel 12 is then accurately positioned with one skin 15 flush with the flanges 13 on one corresponding side of the columns 11, and the caps 19 are then positioned over the other side of the columns 11 and temporarily affixed to the panels 12 as by pressure-sensitive adhesive 29 or the like. A pre-expanded plastic foam composition is then forced through an opening 24 close to the bottom of the main body portion 20 of the cap 19, into the 45 enclosed space of each joint bounded by the cap 19, the panels 12 and the column 11 until this space is filled completely. As the foam 23 solidifies it bonds to the panels

12, the column 11 and the cap 19 and links them rigidly and securely to each other. This solidified foam 23 also seals off the spaces between the panels 12, the column 11 and the cap 19 to provide a weather-tight barrier at each joint.

The cap 19 can be used on either side of the wall joint, but it is always placed on the side where the panels 12 do not rest against a flange of the columns 11. The filling opening 24 in the cap 19 is preferably close to or at the bottom of the cap 19, however, since this assures complete filling of the enclosed space with foam 23. If the opening 24 were near the top, the foam 23 could solidify enough, before it had traveled down to the bottom, to adhere to the enclosing structures and block further passage of foam, creating air spaces which would weaken the joint.

Any number of panels 12 can be placed one upon another to provide a wall of any desired height, so long as the panels are sufficiently strong to support the weight of successive panels. Cross-frame members may of course be used where desired or needed.

As is apparent from the foregoing description, the wall 10 constructed in accordance with this invention is as sturdy and permanent as any curtain wall constructed from the same panels and columns in any manner known to the trade. However, portability involving quick disassembly and reassembly is one of the unique advantages of my invention, and is provided for by including in the joint between the panels and columns a generally U-shaped cutter 25 made from a strong yet flexible length of wire, 25 heavy-duty string, or the like. This cutter 25 is placed abutting the end edges 17 of the panels 12 in an upright or inverted position with long, vertical arm portions 26 adjacent, and preferably abutting the side edges of these panels and a cross over portion 27 adjacent, and also preferably abutting either the top or the bottom edges of the panels 12. The arms 26 protrude out laterally over the top or under the bottom of the column flanges 13 and 14 so that cutter ends 28 are exposed and thus accessible from outside the column. By pulling on the ends 28, 30 the cutter 25 is withdrawn from its position inside the column 11, and the upward or downward travel of the cross-over portion 26 breaks the bond between the foam material 23 and the end 17 of the panel 12, thus releasing the panel 12 from the column 11. Although the cellular plastic foam 23 is strong enough to provide a sturdy, permanent-type bond between the panels 12 and their columns 11, it is weak compared to the severing force exerted by the cutter 25, and it is readily broken down by the slicing action of the cutter 25 as it moves along 35 the side of the panel 12.

In the preferred situation, cutters 25 are placed at each end 17 of each panel 12 so that when the cutters 25 at the two ends 17 of a panel 12 have been removed, the panel 12 is free for removal from between the columns 11. Removal of the panel 12 can then be accomplished simply by hoisting it up from between the columns 11 in a manner the reverse of that by which they are installed. Any excess foam 23 that is left on the panels 12 and columns 11 can be easily scraped off to provide clean 40 surfaces for use when the panels 12 and beams 11 are again erected to form a building. By placing new cutters 25 back in position, disassembly may again be carried out. Since disassembly does not harm the panels 12 and their supporting columns 11, a building constructed according 45 to this invention may be erected and dismantled as often as desired without wear.

Ceilings and roofs

When ceilings or roofs are constructed from sandwich panels according to this invention, the ceiling joists and the rafters are also made from I-beams 11. These are attached to the rest of the building framework in such a manner that their ends are exposed so that the panels 12 can be inserted between adjacent joists or rafters 11

just as they are between adjacent vertical columns 11 in a wall.

Once the panels 12 have been placed between the beams or rafters 11, the cutters 25 are properly positioned and the caps 19 affixed to the panel skins 16. The pre-expanded plastic foam 23 is injected from a convenient point near the eave line and forced under pressure all through the enclosed space in the joints. It makes no difference whether the ceiling or roof is flat, i.e. horizontal, or peaked—the foam 23 will completely fill the space in the joints if sufficient pressure is used.

After the joints in the walls, ceilings and the roof have been filled and bonded in the foregoing manner, the region of the joint between the roof and the walls may be filled and tightly sealed by foaming in place some additional pre-expanded plastic or other suitable composition using conventional procedures now in practice for building insulation. The final result is a completely weather-tight structure of permanent-quality construction, yet which can be swiftly and easily disassembled and reassembled.

Many types of panels or wall, ceiling, and roof enclosures can be joined to this I-beam rigid frame with the method of my invention. However, prefabricated sandwich panels 12 are preferred, since they are easy to handle, quick to install, and possess many other superior qualities. These sandwich panels are made generally from two parallel sheets of aluminum, plywood, cement asbestos board, or other similar sheet-form building material separated by a low density or low cost core material, preferably but not necessarily a cellular plastic. Whatever the panels, they should be fabricated so that their width is slightly less than the distance between the webs 18 of their adjacent supporting columns, joists or rafters 11, but greater than the distance between the edges of the flanges 13 and 14 of the supporting elements 11. Thus the panels 12 will slip in between the supporting elements without rubbing against the webs 18 and yet will not fall out because of the restrictive force exerted by the laterally extending flanges 13 and 14. The thickness of the panels 12 should be sufficiently less than the distance between the two flanges 13 and 14 of a supporting column, etc., to provide a passageway from the foam 23 to get in between the sides of the panels 12 and the webs 18 of the supports.

Various types of foamable plastics may be used in this invention, including phenolics, polyesters, epoxies and polyurethanes, with polyurethanes and epoxies preferred. All these are common, well-known compositions and are commercially available. Polyurethanes are especially advantageous since they now are relatively moderate in cost, are easily handled, and bond tightly to substantially any solid surface with which they come into contact. It is desirable that the plastic components be pre-expanded to a cellular or foam structure prior to any substantial polymerization of the components, and prior to the introduction of the cellular material into the joints between the panels. Use of plastic foaming compositions which are not pre-expanded often results in excessive pressures, limitation in heights to which the foam will rise in the cap, and other difficulties in the fabrication of the structure. Furthermore, the use of a pre-expanded foam permits introduction of the composition at one place only, i.e. at the bottom of the column or end of the beam, rather than at several holes spaced along the column or beam.

If foaming compositions which expand considerably during the polymerization process are used instead of pre-expanded compositions, accurate calculations are necessary to determine the proper quantity to be injected into the several holes spaced along the cap. By using pre-expanded foam, only the amount sufficient to completely fill the cavity within the cap 19 can be easily determined. This enables the foam 23 to be injected at the bottom of a column 11 or one end of a beam and the flow continued until foam appears at the top of the column or the other end of the beam 11, indicating that the cavity is filled com-

pletely. Furthermore, filling by conventional procedures is only a hit-or-miss proposition and quite often results in non-filled voids which weaken the bond.

Since polyurethane and other pre-expanded foams exhibit excellent bond strength to virtually any substrate, it can be seen that this method of injecting the foam at the bottom of the cap or at one end of the cap 19 until it comes out the other end results in a bond of maximum strength. In fact, it has been found that the bond strength between the panels and their supporting beams or columns generally exceeds the strength of conventional fastenings.

To those skilled in the art to which this invention relates, many changes in construction and widely differing embodiments and applications of the invention will suggest themselves without departing from the spirit and scope of the invention. The disclosures and the description herein are purely illustrative and are not intended to be in any sense limiting.

I claim:

1. A curtain wall type of structure, comprising a plurality of spaced-apart I-beams having webs parallel to each other and flanges aligned with each other, each I-beam having one web and two flanges, one on each side of said web, a plurality of sheet-like flat panels each longer than the distance between flanges of adjacent I-beams and each shorter than the distance between the webs thereof and each narrower than the distance between the flanges of a said I-beam, disposed at each end between said flanges of one I-beam and bridging between two I-beams and lying against the flange on one side only of each said I-beam and spaced from the other flange thereof, a rigid cap member on the opposite side of each I-beam from said panel, lying outside of and generally around the opposite flange thereof and having a portion generally parallel to said opposite flange and end portions lying beyond said opposite flange and extending in toward and against said two panels, means adhesively affixing said end portions to said panels, plastic foam filling the space enclosed by said panel, I-beam, and cap and bonded thereto, and a cutting wire at each juncture of a panel with an I-beam, said wire being in said plastic foam and extending across the thickness of said panel and down each side edge thereof and having an end available for pulling, so as to tear said plastic foam and aid thereby in taking down said structure.
2. The structure of claim 1 having an opening adjacent the bottom of said cap, for use in putting in the plastic foam.

3. A method of erecting a curtain wall from I-beam columns, sandwich panels, and rigid cap members of channel configuration, comprising the steps of

erecting said I-beam columns in line with their webs parallel and their flanges collinear and with their webs further apart than the length of the panels and the flanges closer together than the length of the panels, sliding each panel in between each pair of erected I-beam columns, from the end of the columns, between said flanges, abutting each said panel on one said flange at each end, positioning a cutting wire at each juncture of each panel with each I-beam column, extending across the thickness of said panel and down each side edge thereof, placing a said cap over the other flange of each column with its channel surrounding said flange and its end edges engaging two said panels, one on each side of said web, said wire then having an exposed end available for pulling, so that when said wire is pulled it will tear said plastic foam so that said panels can be removed, adhesively affixing said end edges to said panels, and flowing plastic foam into the space defined by said column, panels, and cap, to fill that space and bond to said column, panels, and cap.

4. The method of claim 3 wherein said columns are vertical, said panels are lowered into place from the upper ends of said columns, and each said cap has an opening adjacent its lower end through which said plastic is flowed into said space.
